UNITED STATES PATENT OFFICE.

JOSEPH E. J. GOODLETT, OF MEMPHIS, TENNESSEE.

ATOMIZING-NOZZLE.

1,017,533.

Specification of Letters Patent.

Patented Feb. 13, 1912.

Application filed May 17, 1911. Serial No. 627,869.

To all whom it may concern:

Be it known that I, Joseph E. J. GOODLETT, a citizen of the United States, residing at Memphis, in the county of Shelby and State of Tennessee, have invented certain new and useful Improvements in Atomizing Nozzles, of which the following is a specification.

My invention relates to improvements in atomizing nozzles and is particularly designed and adapted for use in atomizing and projecting hot molasses into a thin falling stream of stock foods or dry base material whereby the latter becomes thoroughly impregnated with the former in the process of treating stock foods as shown and described in my Letters Patent No. 981,549, issued January 10, 1911, for a machine for impregnating stock foods.

The improved atomizing nozzle is designed as a substitute for, and an improvement on the form of atomizing nozzle shown in Figures 3, 4, and 5, of the drawings of said Letters Patent.

The primary object of the invention is to provide a generally improved atomizing nozzle of the class indicated of simple, cheap, and efficient construction, adapted to be readily regulated and controlled to meet the varying demands of actual service.

With the above mentioned and other ends in view, the invention consists in the novel construction, arrangement, and combination of parts, hereinafter described, illustrated in one of its embodiments in the accompanying drawings, and particularly pointed out in the appended claims.

Referring to the drawings, forming a part of this specification, Fig. 1, is a top plan view of a portion of the improved nozzle. Fig. 2, an end elevation of the same. Fig. 3, a sectional view, taken on line 3-3 of Fig. 1.

Similar numerals of reference designate like parts throughout all the figures of the drawings.

The improved atomizing nozzle comprises a liquid supply body or casing 1, forming a liquid supply chamber 2, and provided at its front with a series or bank of atomizing nozzles 3. The atomizing nozzles 3, are preferably of conical shape as shown, and are preferably secured to the supply body or casing 1, by means of threaded base portions 3^a, mounted in internally threaded boss portions 1^a, of the body or casing 1. A bank of air pipes 4, are slidably

mounted in and extend transversely through the liquid supply casing 1, and chamber 2, said air pipes being provided with tapered nozzles 5, disposed within the atomizing nozzles 3, and forming annular liquid supply passages 6, within the walls of the latter, said annular supply passages being gradually constricted toward the tip or nose portions of the nozzles 3, and said nozzles 5, being adapted to be simultaneously moved within the nozzles 3, by the means hereinafter described, whereby to regulate the size and form of the annular supply passages and the amount of liquid flowing therethrough.

As a means for opening and closing the atomizing nozzle 3, as well as providing means for regulating the amount of liquid allowed to pass from the supply chamber 2, through the base portions of the nozzles 3, the air pipes or conduits 4, are provided with annular valve heads 7, adapted to be seated on the adjacent base portions 3^a, of the atomizing nozzles and to be moved toward and from the same with the corresponding movements of the air pipes or conduits 4, and nozzles 5, as hereinafter described.

As a convenient means for removably mounting and securing the air pipes 4, and nozzles 5, within the liquid supply casing 1, the latter is preferably provided with a series of internally threaded boss portions 1^b, adapted to receive and contain a plurality of bearing cups or bonnet members 8, said bearing or bonnet members 8, being adapted to receive and contain the air or conduit pipes 4, and being provided with annular packing glands 9, and gland or packing nuts 10.

As a means for supplying air to the air pipes or conduits 4, a common air supply pipe or casing 11, is mounted upon and carried by the rear ends of said pipes, said pipes being preferably secured to the latter by means of threaded stem portions extending through openings in the supply pipe 11, and secured therein by means of securing nuts 12. The air pipes are adapted to communicate with the air chamber 13, of the supply pipe by means of air inlet openings 14.

The air supply casing or chamber 11, is provided with an air supply pipe 15, communicating with a suitable air compressor 16, adapted to force compressed air into the air chamber 13, and out through the air

pipes or conduits 4, and nozzles 5, and 3, whereby the liquid, such as hot molasses or the like, in the liquid supply chamber 2, will be thoroughly atomized and projecting 5 from the tip or nose portions of the nozzles in a well-known and understood manner. The rear ends of the air pipes 4, are provided with threaded plugs 16, whereby access may be readily gained to the interior 10 portions of the air pipes 4, and nozzles 5, and the ends of the liquid supply body or casing 1, are likewise provided with threaded plugs 17, for a similar purpose.

As a means for simultaneously moving 15 the air pipes 4, and nozzles 5, within the liquid supply body 1, and chamber 2, whereby to regulate the flow of liquid to the atomizing nozzles 3, as well as providing means whereby said nozzles 3, may be closed, a 20 rock shaft 18, is mounted in bearing lugs 19, of the casing, said rock shaft being provided at its ends with crank arms 20, carrying connecting arms 21, pivotally connected to the ends of the air supply member or container 25 11, carried at the rear ends of the air pipes or conduits 4.

As a means for rocking the rock shaft and consequently moving the bank of air pipes 4, and nozzles 5, as desired, a handle 22, is 30 mounted on said rock shaft, said handle being provided with an indicator arm 23, adapted to travel along a graduated scale portion 24*, of a plate 24, whereby the capacity or amount of liquid flowing through 35 the liquid supply passages 6, may be approximately indicated. The liquid supply chamber 2, is adapted to communicate with a suitable source of liquid supply through the medium of a liquid supply or conduit 40 pipe 25, threaded in a threaded boss 26, of the body or casing 1.

From the foregoing description, taken in connection with the accompanying drawings, the operation and advantages of my invention will be readily understood.

Having thus described an embodiment of

my invention, what I claim and desire to secure by Letters Patent is,—

1. In an atomizing nozzle, a liquid supply head provided with atomizing nozzles, an air supply head, and air conduits movable within said atomizing nozzles and provided with valve heads adapted to open and close the latter. 50

2. An atomizing nozzle, comprising a liquid supply casing provided with a bank 55 of atomizing nozzles, a bank of air conduits movably mounted in said casing and provided with air nozzles and valve heads in coöperative relation to said atomizing nozzles, and operating mechanism for moving and adjusting said air nozzles and valve heads. 60

3. An atomizing nozzle, comprising a liquid supply body provided with a bank 65 of atomizing nozzles, a bank of air pipes slidably mounted in said liquid supply body and provided with tapered nozzles disposed within said atomizing nozzles, valve heads carried by said tapered nozzles and adapted 70 to open and close said atomizing nozzles, and means for moving and adjusting said bank of air pipes.

4. An atomizing nozzle, comprising a liquid supply chamber provided with atomizing nozzles, bonnet members and packing nuts at the rear of said nozzles, an air chamber member provided with air conduits mounted in said bonnet members and provided with tapered nozzles extending within 80 said atomizing nozzles and forming annular liquid supply passages therein, a rocking member provided with a handle, and link and crank mechanism connecting said rocking member to said air chamber member, 85

In testimony whereof I have affixed my signature in presence of two witnesses.

JOSEPH E. J. GOODLETT.
